US00D639690S

(12) **United States Design Patent**
Zhu

(10) **Patent No.:** **US D639,690 S**
(45) **Date of Patent:** **** Jun. 14, 2011**

(54) **RING GUIDE**

(76) Inventor: **Xujie Zhu, Yueqing (CN)**

(**) Term: **14 Years**

(21) Appl. No.: **29/383,481**

(22) Filed: **Jan. 18, 2011**

(51) **LOC (9) Cl.** **11-01**

(52) **U.S. Cl.** **D11/3**

(58) **Field of Classification Search** D11/1-7,
D11/26-39; 63/12, 13, 14, 3, 3.1, 3.2, 4,
63/5.1, 5.2, 6; D10/30-32

See application file for complete search history.
